MATTRESS STRUCTURE

Erwin J. Wolf, Fort Wayne, Ind.

Application December 8, 1938, Serial No. 244,623

2 Claims. (Cl. 5—351)

This invention relates to mattress structures, and an object thereof is to provide a mattress with a quilted top and bottom so constituted that the top and bottom quilted units are secured, together with underlying layers of padding, to the adjacent border wires of a complementary spring structure.

Another object of the invention is to afford a method of conveniently and economically securing quilted units in connection with an inner spring structure and the side boxing strip of a mattress.

A further object of the invention is to so form the various units of a mattress structure whereby 15 is eliminated certain parts that ordinarily are required to secure other parts of the structure in place.

Other objects and advantages of the invention will appear in the following description.

20 An illustrative embodiment of the invention is shown in the accompanying drawing, in which:

Fig. 1 is a fragmentary perspective view of one 25 of the quilted units of a mattress in which the invention is incorporated;

Fig. 2 is a fragmentary perspective view of a spring unit that forms part of a mattress structure;

Fig. 3 is a fragmentary detail view in cross-section showing the connection between one of the quilted units and the underlying mattress structure; and

Fig. 4 is a fragmentary view showing an end elevation of the mattress structure, a portion 35 thereof being broken away.

The illustrative embodiment of the invention consists of a mattress having a spring frame unit of usual form provided with border wires 1 that surround a group of coiled springs 2. Upon the 40 top and bottom of the spring frame unit are disposed corresponding layers 3, preferably of sisal, the marginal edges of which initially extend beyond the border wires, and upon the layers of sisal are superimposed corresponding quilted units, each of which is constituted of an under sheet 4, a top sheet 5 and a padding 6 intervening between said sheets.

An especial feature of the invention is the construction of the quilted units that form the 45 top and bottom of the mattress. Preferably, the under and top sheets and the interposed padding are secured together by a course of stitching 7 so applied as to afford a fanciful design. The marginal edges 8 of the under sheet 4 extend 55 initially beyond the marginal edges of the pad-

ding 6 and the top sheet 5, and the marginal edges of the sisal layers also extending initially beyond the border wires 1 of the spring frame unit when in place thereon.

Upon assemblage of the spring frame unit, the 5 layers of sisal and the quilted units in their proper positions, the extending margins 8 of the under sheets of the quilted units are, together with the corresponding margins of the sisal layers, wrapped around the adjacent border wires 10 1 of the spring unit and are secured thereto by means of stitches formed with cord 9 or other fastening means. Thus, the spring frame unit, the sisal layers and the quilted units are at the same time united and held securely together by 15 the stitching afforded by the cord. Also, by covering the border wires 1 with the extending margins of the under sheets of the quilted units and the sisal layers there are formed inner rolls that extend entirely around the mattress.

After the assemblage of the spring frame unit, sisal layers and quilted units has been completed, a side boxing strip 10 is applied around the assemblage, and its top and bottom edges are attached to the marginal edges of the corresponding top sheets 5 of the quilted units, there being preferably applied a binding strip 11 as in the usual manner to conceal and strengthen their respective junctures.

By constructing the mattress as above set 30 forth the under sheets 4 of the quilted units, when attached in place, serve not only to secure the quilted units to the spring unit, but also cover and secure the marginal edges of the sisal around the border wires, and thus is eliminated the usual burlap covering sheets that are 35 commonly employed in ordinary mattress structures. By securing the edges of the side boxing to the top sheets of the quilted units, the edges of the padding of the quilted units as well as the inner rolls are completely concealed, and also the quilted units are held connected together by the boxing strip.

Variations from the particular construction above disclosed may readily be made by exercise 40 of engineering skill without departure from the spirit or scope of the invention, and the following claims are intended to be inclusive of such variations.

What I claim is:

1. A mattress constituted of a spring unit provided with top and bottom border wires, a filling layer on the top and bottom of said unit, a quilted unit covering each of said layers, each quilted unit having top and under sheets and a 55

- padding therebetween secured together, the marginal edges of said layers and the marginal edges of said under sheets extending initially outward beyond the corresponding edges of said padding and being backturned together around the adjacent border wire and secured in place by stitches that extend through said under sheet and layer and the backturned portions thereof thereby to form a roll around the corresponding border wire and under the outer marginal portion of the adjacent padding and top sheet, and a boxing strip the edges of which are secured to the edges of the top sheets of said quilted units.
- 15 2. In mattress construction, a spring unit

having top and bottom border wires, a filling layer on the top and bottom of said unit, the marginal edges of which extend initially outward beyond the corresponding wires, a quilted unit covering each of said layers having top and under sheets and a padding therebetween secured together, the marginal edges of said under sheets extending outward beyond the padding and being secured together with the marginal edges of said layers around said border wires, thus to form marginal rolls supported by said wires and hold said quilted units in place, and a boxing strip forming the outer wall of said structure secured to the edges of said top sheets.
